(57) **CLAIM**

The ornamental design for surgical illuminator, as shown and described.

DESCRIPTION

FIG. 1 is a first broken away isometric view of a surgical illuminator showing my new design;

FIG. 2 is a second broken away isometric view thereof;

FIG. 3 is a broken away front view thereof;

FIG. 4 is a broken away side view looking in the direction indicated by line 4—4 in FIG. 3; and,

FIG. 5 is a broken away side view looking in the direction indicated by line 5—5 in FIG. 3.

The display face of the surgical illuminator (shown in FIGS. 1-3) and body of the surgical illuminator (shown in FIGS. 1-5) are shown in broken (dashed) lines for illustrative purposes only and form no part of the claimed designs.
